US0D1005094S

(12) **United States Design Patent** (10) **Patent No.:** **US D1,005,094 S**
(45) **Date of Patent:** **** Nov. 21, 2023**

(54) **CONNECTOR**

(71) Applicant: **Sur-Loc Holdings, LLC**, Kearneysville, WV (US)

(72) Inventors: **Mark Cerasi**, Kearneysville, WV (US); **Andrew Sneeringer**, Debary, FL (US)

(73) Assignee: **Sur-Loc Holdings, LLC**, Kearneysville, WV (US)

(**) Term: **15 Years**

(21) Appl. No.: **29/806,111**

(22) Filed: **Sep. 1, 2021**

Related U.S. Application Data

(63) Continuation of application No. 16/402,366, filed on May 3, 2019, now Pat. No. 11,286,678.

(57) **CLAIM**

The ornamental design for a connector, as shown and described.

DESCRIPTION

FIG. 1 is a top perspective view of the second embodiment of a connector.

FIG. 2 is a front view of the design as illustrated in FIG. 1.

FIG. 3 is a back view of the design as illustrated in FIG. 1.

FIG. 4 is a right view of the design as illustrated in FIG. 1.

FIG. 5 is a left view of the design as illustrated in FIG. 1.

FIG. 6 is a top view of the design as illustrated in FIG. 1.

FIG. 7 is a bottom view of the design as illustrated in FIG. 1; and,

FIG. 8 is a bottom perspective view of the design as illustrated in FIG. 1.

The broken lines in the drawings illustrate portions of the connector and form no part of the claimed design.

1 Claim, 3 Drawing Sheets
